UNITED STATES PATENT OFFICE

155,173

DESIGN FOR A DISPLAY STAND

Leon Mandel, Chicago, Ill., assignor to Mandel Brothers, Inc., Chicago, Ill., a corporation of Delaware

Application September 11, 1947, Serial No. 141,306

Term of patent 7 years

(Cl. D80—9)

To all whom it may concern:

Be it known that I, Leon Mandel, a citizen of the United States, residing at Chicago, Cook County, Illinois, have invented a new, original, and ornamental Design for Display Stand, of which the following is a specification, reference being had to the accompanying drawing, forming a part thereof.

Fig. 1 is a perspective view of a display stand, showing my new design; and

Fig. 2 is a side elevational view of the display stand.

I claim:

The ornamental design for a display stand, substantially as shown.

LEON MANDEL.
